UNITED STATES PATENT OFFICE.

LOUIS KUEHN, OF LA CROSSE, WISCONSIN.

DESIGN FOR A RAIN-WATER CUT-OFF.

SPECIFICATION forming part of Design No. 31,835, dated November 14, 1899.

Application filed October 19, 1899. Serial No. 734,128. Term of patent 14 years.

To all whom it may concern:

Be it known that I, LOUIS KUEHN, a citizen of the United States, residing at La Crosse, in the county of La Crosse and State of Wisconsin, have invented and produced a new and original Design for a Rain-Water Cut-Off; and I do hereby declare the following to be a full, clear, and exact description of the invention, such as will enable others skilled in the art to which it appertains to make and use the same.

This invention relates to a design for a rain-water cut-off and analogous devices.

The essential feature of the design is a cut-off of Y form, having the outer marginal end portions of the main and branch collars fluted or corrugated and the inner end portions plain.

The design will be more fully comprehended from the following description and the drawings hereto attached, in which—

Figure 1 is a perspective view, Fig. 2 is a top plan view, and Fig. 3 a bottom view, of

a cut-off fashioned in accordance with the outlines of the invention. 25

Corresponding and like parts are referred to in the following description and indicated in all the views of the drawings by the same reference characters.

The cut-off is of Y form in elevation and 30 comprises the main collar 1, branch collars 2, and the divergent pipe-sections 3. The inner end portions of the collars are plain, whereas their outer end portions are fluted, as shown at 4.

Having thus described the invention, what is claimed as new is—

The design for a rain-water cut-off, substantially as herein shown and described.

In testimony whereof I affix my signature 40 in presence of two witnesses.

LOUIS KUEHN. [L. S.]

Witnesses:
